BOOTJACK OR SIMILAR ARTICLE

Arthur S. Cosler, Jr., and Richard K. Patterson,
Columbus, Ohio

Application November 9, 1953, Serial No. 27,500

Term of patent 3½ years

(Cl. D7—2)

Fig. 1

Fig. 2

To all whom it may concern:

Be it known that we, Arthur S. Cosler, Jr., and Richard K. Patterson, citizens of the United States of America, and residents of Columbus, in the county of Franklin and State of Ohio, have invented a new, original, and ornamental Design for a Bootjack or similar article, of which the following is the specification, reference being had to the accompanying drawing, forming a part hereof.

Figure 1 is a perspective view of a bootjack or similar article, showing our new design.

Figure 2 is a cross sectional view taken along line 2—2 of Figure 1.

We claim:

The ornamental design for a bootjack or similar article, as shown.
